UNITED STATES PATENT OFFICE.

CHARLES E. H. RICHARDSON, OF PHILADELPHIA, PENNSYLVANIA.

COFFIN.

Specification of Letters Patent No. 22,537, dated January 4, 1859.

To all whom it may concern:

Be it known that I, CHARLES E. H. RICHARDSON, of the city of Philadelphia and State of Pennsylvania, have invented a new and useful Improvement in the Construction of Air and Damp Tight Caskets for the Preservation of the Dead; and I do hereby declare the following to be a full and exact description of the same, reference 10 being had to the annexed drawings, making a part of this specification, in which—

Figure 1 is a top view of my improved casket, with the top removed, showing an internal lining, hereinafter explained. Fig. 15 2 is a sectional longitudinal elevation, and Fig. 3 a perspective or general view.

The object of my invention is the provision of an air and damp tight casket for the perfect preservation of the dead from 20 decay and the prevention of the escape of any offensive odor or gases. Ordinary coffins have the objections of being vulnerable to decay and the attacks of vermin, and although coffins have been made free from 25 these defects, yet such have been generally made of iron, which is cumbrous and difficult to handle. Or, if made of wood, they have been mostly prepared in such a way as to give them an appearance calculated to 30 disclose at once their object, and necessitate their removal to places specially kept private. I propose to avoid these objections as follows. I make the casket as shown at 35 A, A', Fig. 3, *i. e.*, of an oblong form with circular ends, and of well seasoned wood of some hard and sound species. Inside of this, and covering every part of the sides and bottom and their joints, there is a lining 40 B, B', Figs. 1 and 2, of heavy silk, duck, or other material. This lining I propose to cover with a coat of some suitable paint. Metallic paint would probably answer best, and I would recommend its use. Sheets of smooth, sound, prepared cork are to be 45 provided, which are to be soaked in collodion sufficiently long to fill up the pores and permit the collodion to coat the sur-

faces of the sheets. When the collodion is dry, a coat of oil varnish will be laid on the cork over it, and when the coat of paint on the cloth or silk lining is sufficiently dry, this cork is laid in a proper position on the bottom and around the sides of the coffin, so as to fit snugly to the silk or duck lining. When so placed the joints are to be saturated 55 with such paint as is used on the silk or duck lining.

A lid of strong and heavy plate glass, D, D', Figs. 2 and 3, covers the coffin and is secured in the cork lining by halving or 60 rabbets, and so as to make an air and damp tight joint. Strong bands of plated or other metal, E, E', E'', E''', Figs. 2 and 3, of suitable dimensions, encircle the top and bottom of the casket; the top one being bent 65 so as to resemble in section the gothic letter L. This top band encircles the glass top D, D', as shown in Fig. 2; thus protecting the glass against displacement from jar- 70 ring or the expansion of the air confined within, if the coffin is not exhausted after the remains have been placed in.

Outside of the plate glass lid, D, D', I place a lid of the same kind of wood as that in the body of the coffin. This lid is divided 75 longitudinally into two equal parts, F, F', and F'', F''', Fig. 3, which swing on the hinges G, G', Fig. 3.

If it is desired to exhaust the coffin of air, the body of it might also be coated with 80 the metallic or other paint, and the glass top be braced by any convenient means.

What I claim as my invention, and desire to secure by Letters Patent is—

The construction of a coffin or casket 85 made air and moisture tight by a double lining of cloth and cork, prepared and combined in the manner and for the purpose substantially as above described.

CHAS. E. H. RICHARDSON.
